FOUNDRY MOLDING FLASK

Filed April 29, 1929

Fig. 5.

UNITED STATES PATENT OFFICE

EDWARD PLAYER, OF ASTLEY, NEAR NUNEATON, ENGLAND

FOUNDRY MOLDING FLASK

Application filed April 29, 1929, Serial No. 359,035, and in Great Britain May 18, 1928.

This invention relates to foundry molding flasks, of the kind commonly employed for making sand molds and provided with a locating device at each end by which the upper and lower sections are accurately positioned one on the other.

Frequently the locating devices are parallel sided pins which enter close fitting parallel sided holes at each end or the sides of a flask section. Alternatively, such pins enter a parallel sided hole at one end of a flask section, and an elongated hole or slot at the opposite end. To prevent defective castings, a high degree of accuracy is required in the locating devices and if, through normal use or accident, these pins become out of perpendicular with the joint faces of the mold sections, the latter either cannot be engaged or, through binding, may occasion injury to the mold when opening and closing the latter.

Furthermore, the distance between the centres of the pins or holes varies from time to time due to distortion of the flask sections by the action of heat, or through shocks sustained in normal use. When this occurs, the flask sections cannot be closed together unless there is ample clearance between the pins of one section and the holes of the other so that accurate jointing of the mold is impossible.

The object of the present invention is to provide for use on any ordinary type of flask, locating means which will initially possess and easily retain a high degree of accuracy, even if parts thereof become bent, or the flask sections themselves become bodily distorted, and will allow a number of similar sized flasks to be made interchangeable, whilst permitting easy renewal of the locating means and restoration to the initial accuracy should the parts become seriously damaged.

In the accompanying drawings,

Figure 1 is a perspective view showing the registration means on one end of a pair of flasks,

Figure 2 is a fragmentary perspective view showing the registration means on the other end,

Figures 3 and 4 are elevations showing the essential features of each locating device, and

Figure 5 is a part-sectional view of a modi-

fied form of the locating device shown in Figure 3.

The lower and upper flask sections 2 and 3 may have the usual machined meeting edges at 4 and be provided with trunnions 5 and handles 6 for lifting purposes.

On opposite ends are provided lugs 7 and 8 in one case, and 9 and 10 in the other. To two of these are secured short and sturdy pegs 11 which may be of identical construction and conveniently are arranged so that one depends from the lug 8 on the upper flask 3, whilst the other projects upwardly from the lug 9 on the flask 2.

Each peg may be formed with a shank 65 threaded to engage with its supporting lug as shown, or with a plain cylindrical shank, which is a driving fit in the hole in the supporting lug, and preferably with a collar 12 which abuts the lug or may be sunk therein. The end 13 of the peg is spherical or part-spherical, and between this spherical head and the collar 12 is a neck 14 which may taper to a reduced size where it joins with the head. 70

The spherical head of the depending peg shown in Figure 2 engages closely in a socket formed in the lower lug 7, this socket preferably being constituted by a hardened bush 15 fixed in the lug. The head of the pin, which also is hardened, may fit within the socket with a clearance of approximately half of one thousandth of an inch, and it will be seen that owing to the head 13 being spherical (or being part-spherical, as shown by dotted lines in Figure 3, so that its sides have a spherical curvature) its engagement in the socket is equally exact whether the axis of the peg is coincident with that of the socket or whether, through error in manufacture or subsequent distortion, their respective axes are relatively inclined as is indicated by the two axial lines in Figure 3. Such surety of engagement is also achieved by the formation 80

of the neck 14 which, being of smaller diameter than the head, is not liable to touch the side of the socket even if the peg is tilted relatively thereto. The end of the socket by which the peg enters may be slightly bell-mouthed. 95

The locating device on the opposite end of the flask is shown in Figure 1, the peg employed being preferably identical with that just described but projecting upwardly. 5 The lug 10 with which the peg co-operates is slotted as at 16 so that there is room for relative displacement of the position of the peg in the slot towards or away from the other end of the flask. Extending through each 10 side of the lug 10 into the slot 16 is an adjustable stop 17, the inner ends 18 having flat parallel faces between which the spherical head of the peg is adapted to be engaged with a minimum working clearance. Each of 15 these stops 17 is adapted to be locked by the nut 19 after adjustment for the appropriate clearance.

It is important to notice that the locating pegs are of a short and sturdy nature and 20 that the actual points of location are outside 25 the plane of junction of the two mold sections.

In using the flask sections embodying the present invention, each is employed in conjunction with a pattern plate having locating devices co-operating with those on the respective flask sections. Thus the mold produced is accurately positioned with regard to the locating member or members of its particular 30 flask. When, therefore, the flask sections are assembled, the sections of the mold are accurately located with reference to one another, even if the individual sections of all the 35 locating members have distorted or become damaged from time to time.

If, therefore, through rough usage or warping of the ends of the flask sections, the longitudinal axes of the pegs are out of perpendicular to the plane of the jointing surface between the flask sections, engagement 40 will nevertheless take place without the least danger of the two sections being relatively movable in the plane of division of the mold. Furthermore, at the end of the flask having 45 the ball-and-socket engagement, shown in Figure 3, there will be no binding effects hindering or preventing engagement owing to the fact that the peg can engage quite freely in the socket even when slightly inclined thereto. It will also be seen that the 50 guiding means for the corresponding peg on the opposite end of the flask allow for any changes of centres of the two pegs resulting from the possible above-mentioned 55 distortions and that relative movements in any other direction are restrained. Obviously the size of the end faces 18 of the stops 17 is made sufficient to allow for any such change of centre, and the stops are so mounted in 60 the lug that the faces 18 are at all times parallel with one another.

It will be understood that if desired instead of the one peg engaging in the socket as shown, it could seat, as shown in Figure 65 5, in a part-spherical cup 22 and the latter

could be arranged to move against a spring 23 in guides 24 perpendicular to the jointing surface between the two flask sections, so as to ensure a firm seating contact.

As the pegs project only a comparatively 70 short distance beyond the jointing face, it is desirable to have additional means whereby the upper flask can be guided with a fair degree of accuracy when connecting it with the lower one. For this purpose, guide pins 20 75 (somewhat resembling those ordinarily employed as the locating means for flask sections) are provided. These may be fixed to the lugs in the upper flask and are adapted to enter guide holes 21 in the lugs in the 80 lower flask, which provide a side clearance of about a thirty-second of an inch for the pins. Alternatively, and preferably, loose closing pins may be used in the auxiliary 85 guide holes of the lugs; these can be an easy clearance fit so that there is no possibility of seizing up in the holes. Thus risk of injury of the mold by contact with cores or projecting parts thereon is prevented by the use of the guide pins, and they serve to bring the 90 actual locating means into easy engagement.

It will be seen from the foregoing that the invention ensures, in a cheap and simple manner, accurate location of the several flask sections whether new or after prolonged 95 hard usage, and further it renders similar sized flasks readily interchangeable with one another, so that renewals of broken flasks can be much more cheaply effected than would otherwise be possible. 100

What I claim as my invention and desire to secure by Letters Patent of the United States is:—

1. In a sectional foundry molding flask, the combination of a ball-and-socket register 105 between the flask sections at one end thereof and co-operating parts at the other end which are restrained in every direction except longitudinally of the flask sections.

2. In a sectional foundry molding flask, 110 the combination of a ball on one end of a first section, a co-operating socket on the same end of a second section, a second ball at the opposite end of either of said sections and co-operating guides at the same end of the 115 other section parallel to the length of the flask and restraining the ball laterally.

3. A sectional foundry molding flask having on one end thereof a ball-and-socket locating device between the flask sections, and on the other end a ball on the one section engaging between guides on the other section which are open in a direction towards the opposite end of the flask. 120

4. A sectional foundry molding flask having locating devices by which the upper and lower sections are engaged with one another on opposite sides of the flask, in which each device includes a peg having a spherical sided head, and the head of one device engages in 130

a parallel sided socket providing a fixed location, whilst the head of the other engages between guide surfaces parallel to the length of the flask.

5. Molding flasks as claimed in claim 1, in which the locating device at one end engages parallel guides which are relatively adjustable.

In testimony whereof I affix my signature.

10 EDWARD PLAYER.
